CLAIM

The ornamental design for a tamper evident plastic food container, as shown and described.

DESCRIPTION

FIG. 1 is a front perspective view of a container showing the new design;

FIG. 2 is a rear perspective view thereof with the base having the lid secured thereon;

FIG. 3 is a front elevation view thereof with the base having the lid secured thereon;

FIG. 4 is a rear elevation view thereof with the base having the lid secured thereon;

FIG. 5 is left elevation view thereof with the base having the lid secured thereon;

FIG. 6 is right elevation view thereof with the base having the lid secured thereon;

FIG. 7 is a top plan view thereof with the base having the lid secured thereon;

FIG. 8 is a bottom plan view thereof with the base having the lid secured thereon;

FIG. 9 is a front perspective view thereof with the base having the lid open thereon;

FIG. 10. is a top plan view thereof with the base having the lid open thereon; and,

FIG. 11. is a bottom plan view thereof with the base having the lid open thereon.

The broken line showing of the text in the figures is for illustrative purposes only and forms no part of the claimed design.
